UNITED STATES PATENT OFFICE.

GEORGE B. RYAN AND WILLIAM M. RYAN, OF LEAKY, TEXAS.

RAIL-JOINT.

1,350,182.

Specification of Letters Patent. Patented Aug. 17, 1920.

Application filed November 17, 1919. Serial No. 338,549.

To all whom it may concern:

Be it known that we, GEORGE B. RYAN and WILLIAM M. RYAN, citizens of the United States, residing at Leakey, in the county of

5 Real and State of Texas, have invented certain new and useful Improvements in Rail-Joints, of which the following is a specification.

This invention relates to improvements in 10 rail joints and has for an object to provide rail joints in which the necessity for bolts and the like is eliminated.

Another object of the invention is to provide a rail joint which will firmly hold the 15 ends of rails against displacement.

Further objects and details of the invention will appear as described in connection with the accompanying drawings, and hereafter set forth and claimed.

20 Referring to the drawings, forming a part of this specification, in which like reference numerals designate corresponding parts,

Figure 1 is an elevation showing our improved rail joint; and

Fig. 2 is a sectional view taken on line 2—2 of Fig. 1.

In the drawings, the reference numerals 10 and 11 indicate in general two standard 30 rails using our improved rail joint. In carrying out our invention slots 12 may be milled or otherwise made in the head 13 of the rail with their inner sides forming a continuation of the surfaces of the web 14 of the rail and may extend throughout the 35 length of the rail or just the required distance as will be hereinafter set forth.

The connector element 15 is constructed as best shown in Fig. 2 in the form of a sleeve 40 which has a sliding fit over the base and web of the rail. As illustrated, the upper edges 16 of the connector 15 may extend into the slots 12 in the head of the rail. In cases where the edges 16 extend into these 45 slots 12 in this manner, the outer edges of the slot will retain the sides of the connector 15 in position and reinforce and protect them as will readily be understood.

The operation of our rail joint is as follows: The connector 15 which is in the form 50 of a sleeve is slipped onto the end of one of the rails and to the position illustrated in

dotted lines in Fig. 1. The slots in the rail head being at least as long as the connector, the connector can be positioned so that it 55 will not extend beyond the end of the rail. When it is desired to connect the rails together, the connector is shoved or driven back so that it will engage both rails for substantially the same distance. When in 60 this position it can be fastened by spikes in the usual manner, as illustrated. The connector may be notched in one or more places as at 17 in such a manner that when a spike is driven in place it will fasten the connector against endwise movement, thereby 65 locking the joint.

It will readily be seen that this form of rail joint will allow longitudinal play of 70 the rails necessary for the expansion and contraction of the rails due to variation in temperature and yet hold the ends of the rails in perfect alignment and a solid joint.

We do not wish to limit ourselves to any specific construction or methods as described in this specification for the purpose of giving examples or illustrations of our invention for it is obvious that various changes in the details may be resorted to without departing from the spirit and scope 80 of the invention, which is set forth in the following claims.

Claims:

1. A rail joint comprising a connector sleeve formed from stock of uniform thickness 85 for closely engaging the bases and webs of the abutting ends of two rails and with the upper edges thereof fitting within grooves in the under portion of the heads of the rails, adapted to slide over the end 90 of one of the rails and thereafter be moved to engage the ends of both rails.

2. In a rail joint, the combination with rails having the under portions of their heads grooved, of a connector element there- 95 for in the form of a sleeve made from sheet stock material of uniform thickness and shaped so as to closely engage the surfaces of the bases and webs of the rails and with the upper edges thereof within said grooves. 100

In testimony whereof we affix our signatures.

GEORGE B. RYAN.
WILLIAM M. RYAN.
